UNITED STATES PATENT OFFICE.

LOUIS ANDERSON, OF CHICAGO, ILLINOIS.

HAT-FASTENER.

SPECIFICATION forming part of Letters Patent No. 640,253, dated January 2, 1900.

Application filed August 14, 1899. Serial No. 727,097. (No model.)

To all whom it may concern:

Be it known that I, LOUIS ANDERSON, a citizen of the United States, and a resident of Chicago, county of Cook, and State of Illinois, 5 have invented certain new and useful Improvements in Hat-Pins, of which the following is a specification and which are illustrated in the accompanying drawings, forming a part thereof.

One object of the invention is to provide a neat and efficient means for securing ladies' hats; and a further object is to provide means for securing the hat-pin permanently to the hat, so that it is not in danger of being lost 15 when the hat is out of service. These objects are attained by the construction hereinafter fully described, and which is illustrated in the accompanying drawings, in which—

Figure 1 is a detail inside view of a hat in perspective, showing the hat-pin attached thereto; and Fig. 2 is a detail cross-section through the rim of the hat and a portion of the crown, showing a side elevation of the hat-pin in service.

A frame or plate A is adapted to be secured to the under face and near the inner edge of the rim X of the hat, as shown at a. This frame or plate is provided with a loop or with loops B, and if the frame is in the form of a 25 plate these loops are easily provided by making parallel cuts in the plate and raising the metal between them. The shaft C of the pin passes through and reciprocates in one of these loops, so that it may be thrust forward 30 into the hair of the wearer or may be withdrawn to the position indicated by dotted lines in Fig. 1. Preferably a double-shaft pin is used, as shown in Fig. 1, the two shafts C being united by a cross member D, which 35

40 in this instance constitutes the head of the pin. When a single shaft is used, any suitable form of head may be applied.

The frame or plate A is provided with a spring-tongue E. This may be wrought out in a variety of ways. I show a cheap and effective form of construction in which the tongue is an integral part of the plate and projects laterally therefrom at its inner edge, so as to be located between the two shafts of the pin, and is turned backwardly with a 45 curve and near its end is provided with a shoulder e, which engages the cross member D of the pin when the latter is in its advanced position, and thereby prevents the pin from working out or being accidentally withdrawn. 50 The pin is easily disengaged from the shoulder of the spring E when it is desired to remove the hat and when so disengaged is thrown backwardly, as shown in dotted lines.

While I prefer to make the frame of sheet 60 metal, I do not limit myself to that form, and while I prefer the double-shaft form of pin a single shaft may be used if it is provided with some form of head adapted to engage the spring-detent. 65

I claim as my invention—

In a hat-pin, in combination, a plate for attachment to a hat and having a pair of guide-loops, a spring-tongue secured to the inner edge of the plate and curved backwardly 70 across its face between the loops, and having a backwardly-inclined shoulder near its free end, such end being inclined toward the plane of the plate, and a U-shaped pin adapted to slide under the guide-loops and to engage by 75 its cross member the shoulder of the spring-tongue.

LOUIS ANDERSON.
